UNITED STATES PATENT OFFICE.

AUGUST H. KRUESI, OF SCHENECTADY, NEW YORK, ASSIGNOR TO GENERAL ELECTRIC COMPANY, A CORPORATION OF NEW YORK.

MEANS FOR UTILIZING EXHAUST-STEAM.

1,096,925.

Specification of Letters Patent.

Patented May 19, 1914.

Application filed June 28, 1909. Serial No. 504,673.

To all whom it may concern:

Be it known that I, AUGUST H. KRUESI, a citizen of the United States, residing at Schenectady, county of Schenectady, State of New York, have invented certain new and useful Improvements in Means for Utilizing Exhaust-Steam, of which the following is a specification.

In some power stations having reciprocating and other engines relatively large losses occur due to the ineffective use of the low pressure steam. This is particularly true of stations having non-condensing units.

My invention has for its object to improve the economy of such stations by more completely utilizing the exhaust steam, and for a consideration of what I believe to be novel in my invention attention is directed to the accompanying description and claims 20 appended thereto.

In the accompanying drawing I have shown more or less diagrammatically in Figure 1, one of the embodiments of my invention. Fig. 2 is a diagrammatic view of a motor for 25 operating the valves and a speed governor for controlling it.

1 indicates a mixed pressure elastic fluid turbine which may be of any well known construction. I have shown one of the Curtis condensing type, because it is particularly useful in this connection. It has a plurality of stages—four in the particular embodiment shown. Each stage includes a wheel 2 having one or more rows of buckets 3, two being shown. Between the rows of wheel buckets are stationary or intermediate buckets 4 acting to reverse the direction of the motive fluid and discharge it at the proper angle. Steam is admitted to the first 30 stage by a nozzle 5 and to each of the subsequent stages by a stage nozzle 6 carried by a diaphragm or other fixed part of the turbine. The exhaust from the turbine passes by the conduit 7 to the condenser 8.

45 The admission of steam from the boiler or other source of supply to the turbine is controlled by one or more valves located in a steam chest 9 and responsive to a speed governor 10 that is driven by the turbine shaft. 50 Each valve has a stem 11 that is attached to a lever pivoted at 12 and actuated by a cam mounted on the cam shaft 13. Each valve is given a constant closing tendency by a coiled compression spring 14. The cam 55 shaft is moved by a suitable means, such for

example as a hydraulic motor 15, rack 16 and gear 17. The movements of the motor piston are controlled by a pilot valve 18 and the latter is moved by the speed governor 10. Mounted on top of the turbine is a generator 19 of any approved construction. I have shown a vertical shaft turbo-generator unit but obviously it can be a horizontal unit if desired. The selection of the type and arrangement of the unit will depend largely upon the character of the power station and the work to be performed. Steam from another source, in this case the main or auxiliary header 25 which receives steam from one or more agents such as reciprocating engines or turbines 26, is admitted to an intermediate stage of the turbine. Assuming a four stage turbine the pressures at full load may be as follows: admission 165 lbs. absolute, first stage 52.5 lbs. absolute; second 70 stage 15 lbs. absolute; third stage 4.8 lbs. absolute and the fourth stage 1 lb. absolute. I am giving these figures as illustrations merely and not as limitations of my invention because other pressures may be utilized. 80 As the load on the turbine decreases the stage pressures will decrease not quite in direct proportion to the load but nearly so, so that at no load a very good vacuum will exist in all stages. The pressure in the 85 header will vary somewhat with changes in load on the said agent or agents. Assuming for example the pressure to be about 18 lbs. absolute, a part of the steam will pass to the steam consuming agent 24 which may 90 be a low pressure turbine, or as shown a feed water heater of the open type. The remainder of the steam passes by the pipe 27 through various regulating devices and the nozzle 6 to the second stage of the turbine. 95

The heater 24 is provided with an exhaust pipe 28 that is open to atmosphere and contains a back pressure valve 29 which is loaded to hold a certain definite pressure in the heater—say three pounds above atmosphere 100 for example. A valve controlled vent pipe 30 opening to atmosphere is also provided through which there is a constant circulation of steam to avoid air being pocketed in the heater.

31 indicates a separator for separating lubricating oil from the exhaust steam from the header. Such a device may also be included in the piping leading to the turbine.

In the pipe 27 leading to the turbine is a 110

combined check and stop valve 32. This valve is opened by pressure from the header when the stage pressure falls below a certain value, and is closed by pressure on the 5 turbine side when the stage pressure exceeds that in the header. The valve is provided with a screw threaded stem and hand wheel 33. The lower end of the stem limits the upward or opening movement of the valve, and 10 by screwing the stem downward by the wheel the valve can be positively closed. On the left of the said valve is a butterfly valve 34 that is under the control of the speed governor 10. On the valve stem is an arm 35 that 15 is attached by the link 36 to the lever 37. The lever is operated by a cam located on the cam shaft 13 which is turned by the motor. This cam is so set that it opens the valve 34 in advance of the main nozzle valves and 20 closes said valve after them. In other words whatever be the character of the valve mechanism regulating the admission of live steam to the turbine this butterfly valve precedes it in opening so as to insure a free passage or 25 opening for the exhaust steam from the header 25. If the load on the turbine is small enough to be handled solely by the steam from the header this valve will for the time being act as the turbine regulator, opening 30 and closing as the load changes. Under this condition the valve or valves admitting live steam will be closed. For somewhat greater loads the admission valve or valves may be opening and closing so that a certain 35 amount of live steam is entering the machine.

Between the butterfly valve and the header is an automatic pressure responsive regulator 38. This regulator comprises a valve 39, a 40 diaphragm 40 and a spring or equivalent device 41 that acts in opposition to the pressure from the header. The upper side of the diaphragm is exposed to the pressure on the turbine side of the valve through passage 42, 45 and the under side to atmospheric pressure. The valve 39 is so arranged as to be balanced as nearly as possible. In this embodiment of my invention the balance takes place at atmospheric pressure or slightly above this 50 pressure as determined by the setting of the spring 41.

An advantageous feature of the form of regulator shown is that the diaphragm will be normally covered with water and will 55 keep cool, hence rubber can be satisfactorily employed. Further this arrangement eliminates stuffing boxes and so makes a sensitive device and one free from friction.

Assuming the steam pressure in the header 60 to be 18 lbs. absolute per square inch and that in the second stage of the turbine or other point of admission 15 lbs. absolute or less, the valve 39 of the regulator will open and permit steam from the header to flow 65 through the butterfly valve and the check

valve into the turbine. If there is steam in the stage from another source that of both sources will mingle or mix and pass through the stage nozzle or other fluid discharging devices 6 and act on the next wheel or wheels. 70 If there is no steam from the other source (the boiler in this case) the low pressure steam from the header will perform all the work in the turbine until the load requirements increase. If the pressure of the steam 75 from the header drops below that of the second stage, the pressure of the atmosphere on the diaphragm plus the force exerted by the spring 41 will close the valve 39 of the regulator and the turbine will be operated wholly 80 by steam from the boiler.

It is important to have an automatic pressure regulator to control the flow of steam from the header to the turbine for without it the vacuum due to the condenser would 85 under certain load conditions cause a drop in pressure in the heater, and if sufficiently great the water in the heater would boil violently and cause disturbances which are undesirable. It also prevents air from leaking into the turbine and condenser from the low pressure piping and auxiliaries and impairing the vacuum. The check valve is also important because it prevents steam from the turbine passing into the heater or other 90 auxiliary when the pressure in the connected stage of the turbine rises above the predetermined value as would be the case at loads greater than the rated load or when the turbine is operating non-condensing above 95 half load.

The butterfly valve in addition to its use or function as a regulator under light load conditions of the turbine acts as an emergency valve to shut off steam from the 105 header and prevent the turbine from racing. If desired this valve can also be tripped by the emergency governor of the turbine by causing it to release the connection between the valve and lever 37.

It will be seen that by only modifying the high pressure turbine to the extent of providing it with an opening to receive low pressure steam I can convert it into a mixed pressure turbine. By reason of this arrangement instead of discharging the steam not required for the feed water heater into the atmosphere where it would be wasted, it is discharged into the turbine and performs useful work therein—also that by using 115 steam in this way I am able to take advantage of the greater pressure difference due to the condenser. Whatever steam is admitted to the turbine in this manner results in a direct saving in the cost of operation because less live steam will be required. Under some conditions it is evident that the turbine will require no live steam at all to drive its load.

I have shown my invention in connection 120

with an impulse multistage turbine but it is evident that it can be used in connection with a reaction type of turbine or a combination of the impulse and reaction types.

5 The particular stage to which the low pressure steam is admitted will depend upon the ratio of steam required to drive the auxiliaries to that required for feed water heating, and this in turn depends upon the efficiencies of the auxiliaries, design of the station, manner of operating it, nature of the load the station carries, etc.

I have shown only one connection to the turbine but I may use two or more and in 15 this way utilize steam from several independent sources at different pressures, making similar connections to different stages of the main turbine having appropriate pressures. The reason for this is that auxiliary engines in a power station require an amount of steam which does not fall off very rapidly as the load on the main unit which they serve is reduced. In consequence, below a certain load on the main unit there 25 will in general be too much steam for the auxiliaries and above this load there will usually not be as much as might be utilized for heating the feed water.

I have referred to using exhaust steam 30 from reciprocating engines but my invention is of wider application. For example I can use the exhaust from relatively small low speed turbines operating non-condensing through a relatively small pressure 35 range. Such turbines may be built at a moderate cost and may be direct connected to auxiliary apparatus, *i. e.*, centrifugal pumps, blowers or fans, stokers, exciters or other apparatus. By reducing the pressure 40 range of the auxiliary turbines they may be made to operate at the desired low speeds, and by using their exhaust in the manner set forth the efficiency of the power plant as a whole will be high. It will thus be seen 45 that I am using the term "low pressure steam" in the sense that it is steam which has given up some of its energy to other apparatus before it finds its way into the turbine as distinguished from live steam or that 50 direct from the boiler.

In accordance with the provisions of the patent statutes, I have described the principle of operation of my invention, together with the apparatus which I now consider to 55 represent the best embodiment thereof; but I desire to have it understood that the apparatus shown is only illustrative, and that the invention can be carried out by other means.

What I claim as new and desire to secure 60 by Letters Patent of the United States is:

1. In combination, a steam consuming agent, a conduit receiving the exhaust therefrom, a turbine receiving steam from the conduit and from another source, an automatic pressure responsive regulator in the

conduit which opens when the pressure in the conduit exceeds that in the region in the turbine into which the conduit discharges and closes when the pressure falls below a certain value, and an automatic pressure 70 responsive means arranged between the regulator and the turbine for preventing steam from the turbine from passing through the conduit when the pressure of said region exceeds that in the conduit. 75

2. In combination, a steam consuming agent, a conduit receiving the exhaust therefrom, a turbine receiving steam from the conduit, a regulator in the conduit comprising a balanced valve which is exposed on one side to conduit- and on the other side to turbine-pressure and a diaphragm for actuating the valve, one side of which is exposed to turbine- and the other side to atmospheric-pressure, and a check valve in the conduit 80 between the regulator and the turbine that opens toward the latter. 85

3. In combination, a steam consuming agent, a conduit receiving the exhaust therefrom, a condensing turbine receiving steam 90 from the conduit, a valve mechanism for regulating the admission of live steam to the turbine, a speed governor for controlling said mechanism, a valve in the conduit, a motor controlled by the governor for actuating the valve mechanism and valve, and a self closing valve for preventing the turbine from supplying steam to the conduit when the pressure therein is superior to that 95 in the conduit. 100

4. In combination, a steam consuming agent, a conduit receiving the exhaust therefrom, a condensing turbine receiving steam from the conduit, a valve mechanism for regulating the admission of live steam to the 105 turbine, a speed governor for controlling said mechanism, a valve in the conduit, means controlled by the governor for actuating the valve, and an automatic regulator in the conduit between the agent and 110 said valve which is responsive to pressure in the conduit. 115

5. In combination, a steam consuming agent, a conduit receiving the exhaust therefrom, a condensing turbine receiving steam 120 from the conduit, a valve mechanism for regulating the admission of live steam to the turbine, a speed governor for controlling said mechanism, a valve in the conduit, means controlled by the governor for actuating the valve, an automatic regulator in the conduit between the agent and said valve which is responsive to pressure in the conduit, and a check valve that prevents 125 the turbine from supplying steam to the conduit. 130

6. In combination, a turbine, a condenser therefor, a means for supplying live steam to the turbine, a source of exhaust steam which supplies steam to a region of inter-

mediate pressure in the turbine, valve mechanism by means of which the admission of live steam to the turbine is governed, valve mechanism by means of which the supply 5 of exhaust steam to the turbine is governed, a speed governor that is common to and controls both of said valve mechanisms, and a pressure regulator that is independent of both valve mechanisms and the governor 10 which prevents the vacuum due to the condenser from working back to the source of exhaust steam.

7. In combination, a turbine, a steam consuming agent that exhausts into the turbine, 15 a controlling valve that regulates the admission of high pressure steam to the turbine, a valve that regulates the passage of low pressure steam from the agent to the turbine, a means for positively actuating 20 said valves and a regulator responsive to the pressure of low pressure steam that also controls the flow of fluid between the agent and the turbine, and a valve for preventing the turbine from discharging steam into the 25 exhaust pipe of the agent.

8. In combination, a condensing turbine, valve mechanism for governing the supply of live steam to the turbine, a steam consuming agent, a conduit for conveying the 30 exhaust steam from the agent to the turbine, an apparatus in unrestricted communication with the conduit and receiving a portion of the exhaust steam therefrom, a regulator in the conduit and responsive to pressure on 35 the agent side thereof, a valve in said conduit, a governor that controls the valve and is driven by the turbine, and a check valve that opens toward the turbine from the agent for preventing the turbine from supplying 40 steam to said apparatus.

9. In combination, a high pressure engine, a turbine, a conduit for conveying the exhaust from the engine to the turbine, a condenser, a means for governing the admission 45 of exhaust fluid from the engine to the turbine, a regulator in the conduit which is sensitive to atmospheric pressure and to that of the fluid within the conduit for preventing the vacuum due to the condenser from 50 affecting the engine, a source of high pressure fluid for the turbine, and a means controlling the admission of high pressure fluid when the supply of low pressure fluid is in-

sufficient to satisfy the requirements of the turbine.

55

10. In combination, a high pressure engine, a turbine, a conduit for conveying the exhaust from the engine to the turbine, a condenser, a source of high pressure fluid supply for the turbine, means for regulating 60 the admission of exhaust fluid to the turbine, means for regulating the supply of high pressure fluid to the turbine, a speed governor that is common to and controls both of said means, and a regulator in the conduit 65 which is sensitive to atmospheric pressure and to that of the fluid within the conduit for preventing the vacuum due to the condenser from affecting the engine.

11. In combination, a mixed pressure turbine having a low pressure supply conduit and a high pressure supply chest, a condenser, a valve in the high pressure chest, a valve in the low pressure conduit, a motor that actuates both of said valves, a speed governor for the motor that is sensitive to speed changes of the turbine, and a regulator which is responsive to the difference in pressure between the atmosphere and that of the fluid in the low pressure conduit for interrupting 80 the communication between the conduit and the turbine when the conduit pressure falls below a certain value.

12. In a steam system, the combination of apparatus employing steam, an exhaust line 85 leading therefrom, a low pressure prime mover and a heater connected to the exhaust line, automatically-operated means for insuring the supply of steam to the heater and means for preventing the flow of air from 90 the heater to said prime mover, substantially as set forth.

13. In a steam system, the combination of apparatus employing steam, an exhaust line leading therefrom, a low pressure prime 95 mover and a heater connected to the exhaust line, and means for preventing the flow of air from the heater to the low-pressure prime mover, substantially as set forth.

In witness whereof, I have hereunto set 100 my hand this 26th day of June, 1909.

AUGUST H. KRUESI.
